UNITED STATES PATENT OFFICE.

BYRON A. PIERCE, OF PROVIDENCE, RHODE ISLAND.

DESIGN FOR AN EMBLEM OR SIMILAR ARTICLE.

51,099.

Specification for Design.

Patented July 31, 1917.

Application filed May 24, 1917. Serial No. 170,758. Term of patent 3½ years.

To all whom it may concern:

Be it known that I, BYRON A. PIERCE, a citizen of the United States, residing at the city and county of Providence, State of Rhode Island, have invented a new, original, and ornamental Design for an Emblem or Similar Article, of which the following is a specification, reference being had to the accompanying drawing, forming part thereof.

The figure is a face view of an emblem or similar article illustrating my new design.

I claim:

The ornamental design for an emblem or similar article, as shown.

BYRON A. PIERCE.

Witness:

HOWARD E. BARLOW.
